UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,473, dated December 11, 1883.

Application filed July 23, 1883. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

15 The ground *a* is closely filled in with a small mural ornamentation. Over this ground are various large flower-like figures, with interspersed smaller flower and leaf-like figures, all connected by a network of inconspicuous run-

ning stems. Prominent among the larger figures are the figures marked *A*, *B*, *C*, and *D* in the photograph. These figures are not intended to include the stems that spring out of them. *A* is a large three-part radial figure with a star-shaped center. *B* is a large symmetrical figure resembling an opening flower. *C* is a large symmetrical figure resembling a bulb flower. *D* is a symmetrical open figure. The photograph clearly shows the whole design and the details of the separate figures. 30

I claim—

The design for a carpet, substantially as shown and described.

WINTHROP L. JACOBS.
